UNITED STATES PATENT OFFICE.

OLAF LARSEN, OF FORT ATKINSON, WISCONSIN, ASSIGNOR TO THE CREAMERY PACKAGE MFG. COMPANY, OF CHICAGO, ILLINOIS, A CORPORATION OF ILLINOIS.

BOTTLE WASHING AND STERILIZING APPARATUS.

Application filed October 8, 1923. Serial No. 667,220.

The invention relates to machines for the washing, rinsing and sterilizing of bottles, more particularly to an automatic machine adapted to the cleansing of milk bottles by means of pressure jets of washing and sterilizing fluids.

Apparatus of this type heretofore have been produced generally in large units in connection with automatic receiving and delivering devices for the handling of large quantities of bottles in dairies and milk plants of large size.

It is the principal object of this invention to provide a machine of economical construction and efficient operation for use in small dairies using a limited quantity of bottles and without extensive conveying systems for the latter, and requiring the minimum of attendance in the operation of the machine.

Other objects and advantages will be apparent in the following description of a preferred embodiment of the invention which I have selected for illustration herein. It will be understood, however, that various changes in form, construction and arrangement may be made by those skilled in the art without departing from the spirit and scope of the invention as expressed in the appended claims.

Referring to the drawings, Fig. 1 is a plan view of the machine having the carrier belt and bottle holding pockets removed to disclose the underlying structure. Fig. 2 is a side elevation of the machine and Fig. 3 an end elevation, both figures also showing the carrier as being removed and having portions of the end and side walls removed to disclose the interior construction. Fig. 4 is a fractional plan view of the rear end of the machine showing the carrier belt and bottle holding pockets in position, and the means for driving the carrier. Fig. 5 is a fractional sectional elevation of the rear end of the machine. Fig. 6 is a similar fractional elevation of the front end of the machine. Fig. 7 is a fractional sectional view of the conveyor supporting guide rails with a detailed view of one of the bottle holders.

Stated generally, the machine comprises a divided tank over which operates a horizontally positioned endless carrier having pocket holders for the carrying of bottles in inverted position. One run of the carrier operates over one section of the tank wherein are devices for the washing of the bottles by pres-

sure jets as they progress through the tank. The return run of the carrier conveys the bottles through the other section of the tank wherein rinsing and sterilizing devices are provided for the treatment of the bottles by pressure jets. The machine is so arranged that a single operator may place dirty bottles on the carrier and remove the treated bottles, performing both operations manually at one end of the machine as the carrier passes around its supporting sheave, the latter being positioned on a table extending outwardly from the tank whereat the carrier pockets are conveniently accessible.

More specifically described, with reference to the drawings, the reference numeral 1 indicates a tank, herein illustrated as of rectangular form, supported by upright standards 2 suitably secured to the side walls of the tank and extending therebelow to give a substantial clearance beneath the tank. The bottom 3 of the tank is preferably inclined towards its front end.

A partition 4 divides the tank into two compartments, the compartment 5 being adapted to contain a suitable washing solution, and the other compartment 6 a rinsing fluid, together with mechanism for the application of the fluids to the bottles, more fully described hereinafter.

Secured to the front and rear ends respectively of the tank are a pair of table supports 7 and 8 on which are pivoted the idler sheaves on which the carrier is supported. The side walls of the tank extend above the horizontal position of the tables as indicated at 9, and are preferably surmounted by a cover 10 forming a chamber over the tank for the operation therein of the spraying devices upon the bottles carried by the conveyor, and from which the spent liquids drain back into the lower portions of the tank.

The front table 7 is constructed with an upwardly extending flange 11 forming a lateral enclosure about the table, the latter having its bottom portion extending over the end wall of the tank, preferably with a downwardly turned flange 12 adapted to carry water draining from the bottles upon the table over the tank wall and into the respective compartments. (See Fig. 6.) An inward extension 13 is also provided in each compartment for the support of the carrier guide rails herein-after described.

A bearing block 14 is mounted on the bot-

tom of the table 7, having a longitudinally slidable support thereon, and adjustably secured thereto preferably by means of a bolt 15 carried by the block and extending through an elongated slot 16 in the bottom of the table. The bearing block 14 carries an upright pivot pin 17 on which is mounted a sheave 18 positioned for rotation on a horizontal plane, the sheave and pin preferably being operatively secured to the bearing block by means of a removable set screw 19 mounted in the bearing block and extending into an annular groove in the pivot pin.

The bearing block 14 is also provided with a semi-circular guide 20 constructed with a flat bearing portion 21 and a concentric shoulder 22 for the support of the carrier pockets, hereinafter described, in their passage about the sheave.

20 The rear table 8 is also constructed with an upstanding lateral flange 23 forming a basin for drainage from the table into the tank, its bottom also provided with a downwardly extending flange 24 positioned inwardly of the rear end wall of the tank, and having also a pair of rail supports 25 integral therewith. A second horizontally positioned sheave 26 is supported on the rear table 8, having a pivot pin 27 operatively supported in a bearing 28 formed in the bottom of the table. The table 8 is also provided with a curved supporting guide 29 for the carrier pockets, having a flat bearing surface 30 with an upraised inner portion forming a lateral shoulder 31.

40 A driving sprocket 32 is positioned on the rear table 8 laterally of the sheave 26, and is mounted on a drive shaft 33 extending through a suitable bearing 34 in the bottom of the table and downward to the bottom of the tank, where driving means is provided as hereinafter described.

45 Secured on the rail supports 13 and 25 provided on the tables 7 and 8 at the respective ends of the two compartments of the tank, is a pair of guide rail structures extending through the upper portion of each of the compartments, respectively. As herein illustrated, the latter structure comprises a lower rail 35, (see Fig. 7) and an upper rail 36, the upper rail being supported from the lower, as by means of the upright brackets 37, rigidly secured to the two rails.

50 Operating between the spaced rails 35 and 36 and supported at the front and rear ends of the machine by the sheaves 18 and 26, is an endless carrier 38, preferably of pivoted link construction, the links passing in operative engagement with the offset driving sprocket 32 by which the carrier is operated.

55 Spaced at regular intervals on the carrier 38 are bottle receiving pockets or holders 39. As herein illustrated, the holders are rigidly secured to individual links of the chain carrier, and comprise a cup shaped annular struc-

ture, open at the top and bottom, and having an inwardly inclined inner surface on which are provided vertical ribs 40, the latter ending in inturned end portions 41 for the support of the mouth end of an inverted bottle. 70 The spaces between the ribs provide for the passage of the cleansing fluids about the bottles positioned in the holders, and the latter are also provided with lateral openings 42 between the ribs for further access of the 75 cleansing fluids to the bottles.

80 Each of the holders is laterally provided at its upper edge with an extension 43, having a slot 44 extending across its upper face which is adapted to engage the upper rail 36, the latter passing through the slot 44 as the holder progresses through the tank. A lower lateral extension 45 is also provided on its under surface with a slot 46 which engages the lower rail 35. The holders are thus supported in their passage through the machine in upright position and accurately guided over the jets within the tank compartments. 85

90 In the travel of the holders about the sheaves at the front and rear ends of the machine, their lower extensions 45 bear upon the guides 20 and 29, provided in the bottom portions of the front and rear tables, and are secured in upright position by their lateral abutment with the shoulders 22 and 31. The 95 carrier chain may be maintained without slack by adjustment of the bearing block 14 upon its support in the bottom of the front table 7.

99 The tank compartment 5 is adapted for the 100 employment of a suitable solution for the first washing or cleansing operation, the circulation of the solution being accomplished by means of a pump 47 (see Fig. 2) mounted on the horizontal supports 48 carried by 105 brackets 49 secured to the tank supports 2. An intake pipe 50 is connected through the end wall of the tank compartment with a tubular screen 51, the solution being discharged from the pump through a pipe 52 110 entering the tank through its lateral wall, and supplying liquid to the horizontal header 53 aligned beneath the path of the bottle holders on the carrier. The header 53 is provided with a plurality of jet orifices 54 positioned 115 in its upper surface, which are arranged to spray the washing solution within and without the bottles as they pass thereover.

120 There is preferably provided also in compartment 5, means for a cold water preliminary rinse comprising a horizontal header 55, having similar jet orifices 56 in its upper surface and connected by the pipe 57 with a supply pipe 58, leading from a source of 125 supply of fresh water and controlled by the valve 59. In order not to dilute and cool the solution contained in the washing compartment, a removable pan 60 may be located beneath the cold water spray head 55 adapted to receive the falling spent water. The pan 130

60 is shown extending through the side wall of the tank, its inner end suspended by a strap from the rail 35. A drain tube 61 discharges the water collected by the pan without the tank.

For washing the outer sides of the inverted bottles there may be further provided an overhead spray herein illustrated as comprising the pipe header 62, positioned in the upper part of the enclosure through which the conveyor travels, and having jet orifices in its lower surfaces adapted to spray from above the passing bottles. The spray pipe 62 is connected by the pipe 63 with the discharge pipe 52 leading from the pump 47.

After the bottles have passed through the washing compartment and around the rear sheave 26, they enter the other compartment 6, wherein they are subjected to rinsing and sterilizing operations. The rinsing is preferably done by clear water contained in the compartment and circulated for spraying the bottles by means of a second pump 64, (Fig. 2) mounted on the supports 48, and having an intake pipe 65 leading across the rear end of the tank and through the rear end wall of the compartment 6 to the intake tubular screen 66. The rinse water is discharged from the pump through a discharge pipe 67, extending through the tank and terminating in the header 68, having jet orifices 69 regularly spaced in its upper surface beneath the center line of the path of the bottle conveying holders. The bottles may be outwardly rinsed by means of the overhead spray pipe 70, having jet orifices in its under surface and connected with the discharge pipe 67, through the pipe 71.

After being rinsed the bottles are conveyed over sterilizing jets provided in the short header 72, positioned beneath the path of the bottles at the front end of the compartment and having spaced jet orifices 73, positioned to inject hot steam into the passing bottles, the header 72 having a pipe connection 74 with a steam supply line 75, leading from the front end of the machine, the sterilizing jets being controlled by the valve 76.

The liquids in the two compartments of the tank may be heated to the desired temperature by means of the suitably constructed steam heaters indicated at 77, within each of the tanks, and supplied with steam through the connections 78 from the steam line 75, the heaters being individually controlled by the valves 79. The tanks may be supplied with water as required through the discharge outlets 80, entering the front end of the respective compartments and respectively controlled by the valves 81 having pipe connections 82 with the water supply line 58.

As herein illustrated, the two pumps 47 and 64 are preferably operated with a common drive shaft 83, (see Fig. 2) and posi-

tioned thereon intermediately of the pumps is a pulley 84, having a belt connection with a driven pulley 85, mounted on the shaft 86, having suitable bearings in supports 87 and 88 carried by the outer supports 48 and the end structure of the tank. A worm 89 mounted on the shaft 86, operatively engages a worm gear 90, mounted on the upright shaft 33, carrying the carrier driving sprocket 32. The shaft 33 has its lower bearing in the gear housing 91 mounted on the rear end of the tank. A pulley 92 carried by the pump shaft 83 is provided for suitable connections with a source of power for the operation of the machine.

In operation the attendant standing at the front end of the machine will have conveniently at hand cases of bottles to be washed and manually place them in the pockets of the carrier as the latter passes around the front supporting sheave, removing the bottles after they have passed through the washing and the rinsing and sterilizing compartments as they return over the front table of the machine and replacing them in the cases. It will be observed that all of the control valves for the adjustment of the pressures and supply of the several fluids being used, are located conveniently to the hand of the operator at the front end of the machine.

I claim as my invention:

1. Apparatus of the class described comprising a tank longitudinally divided into two compartments, means for washing bottles in one of said compartments, means for rinsing bottles in the other of said compartments, a pair of tables secured outwardly of the ends of said tank respectively and extending across the ends of said compartments, a sheave pivoted upon one of said tables, a second sheave pivoted upon the other of said tables, an endless carrier operatively supported on said sheaves and having one run passing through one of said compartments and the other run passing through the other of said compartments, a series of spaced holders mounted on said carrier adapted to receive inverted bottles and convey said bottles through said compartments for operation thereupon by said washing means and said rinsing means, and means for operating said carrier.

2. Apparatus of the class described comprising a tank, bottle cleansing means in said tank, a table secured without one end of said tank having a sheave pivoted thereon, another table secured without the other end of said tank also having a sheave pivoted thereon, an endless carrier operatively supported on said sheaves, and passing through said tank, a series of bottle holders secured laterally on said carrier, rails in said tank for the guiding support of said holders in their passage therethrough, and guides on said tables concentric with said sheaves for the support

of said holders in their passage over said tables.

3. In apparatus of the class described, having a tank and means therein for cleansing bottles, the combination of an endless carrier positioned with its runs passing through said tank, a pair of tables secured respectively at each end of said tank, a pair of sheaves pivoted respectively on each of said tables and operatively supporting said carrier, a series of bottle holders laterally secured on said carrier, and curved guideways on said tables respectively, said guideways being adapted to receive and support the laterally extending bottle holders in their passage with said carrier about said sheaves.

4. In apparatus of the class described, having a tank and means therein for cleansing bottles, the combination of an endless carrier positioned with its runs passing through said tank, a series of laterally attached bottle holders on said carrier, a table secured at one end of said tank having a sheave pivoted thereon for the operative support of said carrier and having a guideway for the support of passing bottle holders, another table secured at the opposite end of said tank, a block adjustably positioned on said latter table, a

sheave pivoted on said block for the operative support of said carrier, and a guideway 30 formed on said block in concentric relation to said sheave adapted to support said holders in their passage about said second mentioned sheave.

5. Apparatus of the class described, comprising a tank, bottle cleansing means in said tank, an endless carrier positioned with its runs extending through said tank, a pair of tables secured respectively at each end of said tank, a pair of sheaves pivoted respectively on each of said tables and operatively supporting said carrier, a series of laterally extending bottle holders secured on said carrier, curved guideways on said tables adapted to support said bottle holders in their passage about said sheaves, and a pair of spaced rails positioned adjacent each of the runs of said carrier through said tank and extending between the ends of said guideways, said rails having lateral sliding engagement with 50 one side of said holders to guidingly support said holders in operative relation to said cleansing means.

In witness whereof I have hereunto attached my signature.

OLAF LARSEN.
